RICHARD WILLM. BINNS, OF WORCESTER, COUNTY OF WORCESTER,
ENGLAND.

DESIGN FOR A VASE.

Design No. 20,060, dated July 29, 1890.

UNITED STATES PATENT OFFICE.

RICHARD WILLM. BINNS, OF WORCESTER, COUNTY OF WORCESTER,
ENGLAND.

DESIGN FOR A VASE.

SPECIFICATION forming part of Design No. 20,060, dated July 29, 1890.

Application filed April 21, 1890. Serial No. 348,917. Term of patent 7 years.

To all whom it may concern:

Be it known that I, RICHARD WILLIAM BINNS, director of the Royal Porcelain Works, Worcester, and a subject of the Queen of Great Britain, residing at Worcester, in the county of Worcester, in the Kingdom of Great Britain, have invented and produced a new and original Design for a Vase, of which the following is a specification, reference being had to the accompanying photograph, forming a part thereof.

The leading features of the design are as follows: a short slightly-conical base, a beaded groove separating it from the body, a plane ovate body, a cylindrical neck ornamented in bass-relief, a double-fluted salient cone with rabbets above and below, and an expanding fluted mouth resembling a daffodil corolla. Two conventional feathered dolphins section is circular throughout, except, of course, the dolphins.

What I claim is—

The design for a vase herein shown and described, the same comprising a base, an ovate body, cylindrical ornamented neck, double salient cone above with rabbets, conventional dolphins uniting body of cylindrical portion and cone and forming ornamental handles, and daffodil-corolla-shaped mouths. 30

In testimony whereof I have signed my name to this specification in the presence of two subscribing witnesses.

RICHD. WILLM. BINNS.
